UNITED STATES PATENT OFFICE.

GEORGE W. STORCH, OF APPLETON, WISCONSIN.

CARBURETER.

1,272,561.

Specification of Letters Patent. Patented July 16, 1918.

Application filed October 19, 1916. Serial No. 126,486.

To all whom it may concern:

Be it known that I, GEORGE W. STORCH, a citizen of the United States, residing at the city of Appleton, county of Outagamie, 5 and State of Wisconsin, have invented new and useful Improvements in Carbureters, of which the following is a specification.

My invention relates to improvements in carbureters, and it pertains more especially 10 to that class which are used for supplying explosive mixture for automobile motors.

The object of my invention is to provide a more simple and inexpensive carbureter than those heretofore made, in which all floats and 15 springs are dispensed with, and whereby the same may be used on rough or uneven roads without liability of the gasolene or other liquid fuel being spilt, and without the liability of easily getting out of order. Also 20 by which there is no danger of an automobile burning from back fire, etc.

My invention is further explained by reference to the accompanying drawing, in which—

25 Figure 1 represents a vertical section, drawn on line 1, 1 of Fig. 2, and

Fig. 2 is a plan view.

Like parts are identified by the same reference numerals throughout both views.

30 Gasolene or other liquid fuel is led to the carbureter through the duct 1, when it passes thence up through the duct 2 and the flow of gasolene to the carbureter is controlled by the manually actuated valve 3, said valve 35 being provided with a screw thread 4 and a chased hand nut 5 by which it is adapted to be turned forwardly and backwardly as may be required to open and close said duct 2.

40 Air is simultaneously admitted with gasolene or other liquid fuel to the carbureter through the duct 6, when it passes the baffle plate 7 through the opening 8 and the baffle plate 9, when it becomes thoroughly mixed 45 with gasolene, whereby the gasolene is converted into an explosive mixture.

10 represents a duct which leads to a motor, not shown. It will be understood that with each forward movement of the piston 50 in the motor a partial vacuum is formed in the duct 10 and mixing chamber 11, whereby the valve 12 is automatically raised with each forward stroke of the piston, and whereby the gasolene vapor which has been generated 55 in the carbureting chamber 13 passes thence to the motor.

The gasolene is admitted to said carbureting chamber 13 through the port 14, and said port is opened and the valve 15 withdrawn from the passage 2 with each up-stroke of the valve 12, and said valve 12 together with the valve 15 and sleeve 16 are forced downwardly to near the closed position, shown in Fig. 1, by the revoluble movement of the curved member 17 which rests 60 upon the upper side of the collar 18.

Attention is called to the fact that the collar 18, sleeve 19, sleeve 16 and valves 12 and 15 are all connected together by threaded joints and are all adapted to be simultaneously moved downwardly by the movement of the curved member 17, as the same is brought to the position shown in Fig. 1, whereby the large valve 12 and valve 15 are both simultaneously brought to near their 70 seats. When, however, the motor is started the member 17 is moved toward the right, reference being had to both Figs. 1 and 2, whereby the upper end of the member 17 is brought above the collar 18, and whereby 80 said valves are both free to be lifted by the upward pressure of the combustible mixture beneath the lower side of said valve 12. The curved member 17 is pivotally supported from the duct 10 by the vertical bolt 85 20, hub 21 and arms 22 and 23.

To the free upper end of the member 17 is a lever 24 which is connected therewith by the bolt 25, whereby motion is manually communicated to the carbureter by moving 90 said lever 24 from left to right, as previously stated, and whereby the supply of combustible mixture is cut off by the reverse movement of said lever 24, whereby said valves are brought to the position shown in Fig. 1. 95

Attention is called to the fact that the carbureter may be supplied with a greater or less quantity of gasolene, regardless of the movement of the valves 12 and 15 by the adjustment of said valve 3. Also that by 100 turning said valve 3 inwardly the entire supply of gasolene will be shut off. Attention is also called to the fact that in case of back fire from the motor the valves 12 and 15 will both be simultaneously and quickly 105 closed, whereby the liability of a fire leading to the gasolene in the carbureting chamber 13 is entirely obviated.

It will be understood that the mixture controlling valves 12 and feed controlling valve 110 15 are not forced entirely to their seats by the action of the curved bearing 17, but in-

stead said valves are permitted to drop entirely to their seats of their own gravity preparatory to stopping the motor. It therefore follows that when the bearing member 5 17 is turned toward the left, to the position shown in Fig. 1 of the drawings, said mixture controlling valves 12 and feed controlling valve 15 are permitted to remain partially open, and a small quantity of fuel sufficient to operate the motor slowly is permitted to pass said valves, whereby the motor is permitted to run slowly until the igniting mechanism is turned off. The valve 12 is rigidly connected to the sleeve 19 and said 10 valve 12 is held partially open by the threaded ports of said sleeve with the inclosed sleeve 16, as shown in Fig. 1. The valve 15 is permanently connected with the rod 26 and said rod is in turn threaded to the inner wall of said sleeve 16 when it is also held partially open.

Having thus described my invention what I claim as new and desire to secure by Letters Patent, is:—

25 1. In a device of the described class, the combination of a carbureting chamber provided with both air and gasolene inlet ducts, a valve for controlling the passage through one of said ducts, a mixing chamber located 30 in close proximity to said carbureting chamber, a mixture actuated valve for controlling the passage of said combustible mixture from said carbureting chamber to said mixing chamber, manually actuated means for simultaneously forcing both of said last 35 named valves toward their seats, both of said valves being connected together and adapted to be simultaneously opened by the pressure of said combustible mixture as it 40 passes from said carbureting to said mixing chamber.

2. In a device of the described class, the combination of a carbureting chamber provided with both air and gasolene inlet ducts, 45 a valve for controlling the passage of gasolene from one of said ducts to said carbureting chamber, a mixing chamber located in close proximity to said carbureting chamber, a mixture actuated valve for controlling

the passage of combustible mixture from 50 said carbureting chamber to said mixing chamber, manually actuated means for simultaneously forcing both of said last named valves toward their seats, comprising an inclined circular bearing revolvably supported 55 above said valves, said bearing being adapted as it is turned in one direction to force said valves toward their seats, and when turned in the opposite direction to permit said valves to be opened by the pressure of 60 said combustible mixture against the lower side of said mixture controlled valve, both of said valves being connected together and adapted to be simultaneously opened by the pressure of said combustible mixture. 65

3. In a device of the described class, the combination of a carbureting chamber provided with both air and gasolene ducts, a manually actuated valve for controlling the passage of gasolene through said gasolene 70 duct, a second valve for controlling the passage of gasolene from said duct to a mixing chamber, a mixing chamber located in close proximity to said carbureting chamber, a large valve for controlling the passage of 75 combustible mixture from said carbureting chamber to said mixing chamber, manually actuated means for forcing said controlled valve toward its seat, said valve being adapted to be opened by the passage of combustible 80 vapor from said carbureting chamber to said mixing chamber, an inclined curved bearing revolvably supported above said last mentioned valve, said bearing being adapted as it is moved in one direction to force said 85 valve to its seat, and when moved in the opposite direction to permit said valve to be opened by the pressure of the combustible fluid in said carbureting chamber, and a hand actuated lever affixed to said curved 90 bearing, all substantially as and for the purpose specified.

In testimony whereof I affix my signature in the presence of two witnesses.

GEORGE W. STORCH.
